UNITED STATES PATENT OFFICE.

CHARLES T. DE BRISAY, OF OTTAWA, ONTARIO, CANADA.

PRINTER'S CHASE.

No. 913,946.

Specification of Letters Patent.

Patented March 2, 1909.

Application filed March 30, 1908. Serial No. 424,272.

To all whom it may concern:

Be it known that I, CHARLES T. DE BRISAY, residing at Ottawa, in the county of Carleton, Province of Ontario, and Dominion of Canada, have invented new and useful Improvements in Printers' Chases, of which the following is a specification.

My invention which will be hereinafter fully set forth and claimed relates to appliances for locking up type and other printing matter and for holding unmounted plates.

The object of my invention is a chase that is adjustable to the matter which it is desired to use for printing, be it blocks, plates or type or one or more of these combined, locking the matter without the aid of quoins and furniture. Also for securing plates without the necessity of using blocks specially prepared for that purpose.

20 Figure 1 is a face view of my adjustable chase, locking up blocks and type. Fig. 2 is a side view of the same. Fig. 3 is an end view of the same, partly in section. Fig. 4 is a transverse section of the same, on line 25 4—4, Fig. 1, and Fig. 5 is a profile of a plate holder.

A foundation or backing, A, for a plate to be used for printing is made up of sections, 1, 2, 3, 4 and 5; B represents type and C leads, 30 making up a page to be printed. The block A may be in one piece.

A pair of side bars, D D, of rectangular cross section, plain and of a depth or height somewhat less than the width or height of a 35 lead or the depth or height of quads is provided. They are preferably plain longitudinally. These are engaged by two end-bars, E E, each made in two lengths or sections and each section left short, so that a free space or 40 gap is left in the center. They are of greater depth or height than the side bars, being about equal in height to the quads and leads. The ends are saddled upon the sides, D, a 45 rectangular opening check or gap, 6, being made near each end which is equal to the cross section of the side bar, open at the bottom and an easy fit, so that these end bars may slide upon the side bars. Each pair is connected by a right and left handed screw, 50 E¹, threaded into the opposing ends and having a medial angular head, e¹, to which a key may be applied. By tightening these screws

the side bars are drawn together and tightly clamp the matter standing between them.

To hold a plate upon the backing A, plate 55 holders, F, are used, shown separate in Fig. 5. They each consist of a plate shank nearly type high and having an integral head, f, flush with the shank on one side but curved at the top and projecting laterally over the 60 other side, the inner face, 7, being beveled downwards and inwards, to form a claw with a dovetail hold on the beveled edge of a plate. They may be of any length and one or more may be used on each side, being inserted 65 between the side bars and the backing and with or without leads.

Type and other matter standing in a gallery may be locked up in these adjustable chases and handled and transported with 70 facility and without danger of being "pied". Their use makes galleries for standing type unnecessary. They also afford a cheap and efficient means for printing from unmounted plates.

75 I claim as my invention;—

1. In an adjustable chase, the combination of a pair of rectangular side bars, two pairs of end bars of greater height than the side bars engaging the latter and a right and 80 left handed screw connecting the opposing ends of each pair of end bars and having a medial head substantially as set forth.

2. In a form holder, the combination of two rectangular side bars, two pairs of end 85 bars of greater height than the side bars and having openings near the outer ends through which the side bars pass slidingly, a right and left handed screw threaded into the inner or opposing ends of each pair of end bars and 90 having a medial head, a plate backing adapted to be inclosed within said bars, leads surrounding said backing and a series of plate holders inserted in said leads and at the sides of the backing and consisting of plate shanks 95 having claw heads adapted to engage the plates, substantially as set forth.

In testimony whereof I have affixed my signature, in presence of two subscribing witnesses.

CHARLES T. DE BRISAY.
